(57) **CLAIM**

The ornamental design for a frame of kids swing chair as shown and described.

DESCRIPTION

FIG. 1 is a front view of a frame of kids swing chair showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a perspective view of a frame of kids swing chair shown in an environment of use;

FIG. 9 is an enlarged detail view of the encircled area at 9 in FIG. 6; and,

FIG. 10 is an enlarged detail view of the encircled area at 10 in FIG. 6.

The seat and arms shown in broken line in FIG. 8 show environment that forms no part of the claimed design. The encircling lines in FIG. 6, 9, 10 illustrate the border of the enlarged detailed views and form no part of the claimed design. All other broken lines show portions of the article that form no part of the claimed design.

1 Claim, 10 Drawing Sheets
